UNITED STATES PATENT OFFICE

ERAND M. MUNCHERIAN, OF ATLANTA, GEORGIA

FUSE PLUG

Application filed September 13, 1928. Serial No. 305,735.

The present invention relates to fuse plugs adapted particularly for house circuits and has for its principal object to provide a plug of this character equipped with a multiplicity of fusible links adapted to be successively connected in the circuit and thus enable the circuit to be constantly maintained in closed condition upon the fusing or blowing out of any of the links due to the overloading of the circuit, and without necessitating the removal of the plug from its socket.

A still further object of the invention is to arrange the series of fusible links concentrically within the plugs and providing a pivotally mounted switch member adapted for engagement with any one of said links and providing means for releasing the switch member from the fusible links with which the same is in contact and after the same has become fused so that the switch may be moved into contact with another of said links.

An additional object is to provide a spring means for actuating the switch so as to automatically move the same into contacting engagement with a fresh link.

A still further object is to provide a fuse plug of this character of a simple and practical construction, which is efficient and reliable in performance, relatively inexpensive to manufacture and install in operative position and otherwise well adapted to the purpose for which the same is intended.

Other objects and advantages reside in the special construction, combination and arrangement of the various elements forming the invention as more fully hereinafter described and claimed, reference being had to the accompanying drawings forming part hereof, wherein like numerals refer to like parts throughout, and in which in the drawings:

Figure 1 is a vertical sectional view through the assembled plug,

Figure 2 is a top plan view,

Figure 3 is a view in side elevation with parts broken away and illustrating one of the compartments within the plug for each of the fusible links, and

Figure 4 is a transverse sectional view taken substantially along a line 4-4 of Figure 1.

Referring now to the drawings in detail, the invention comprises a fuse plug of the character generally employed in house electric circuits and composed of a cylindrical body member 5 of porcelain or other insulation material having a series of concentrically arranged longitudinally extending compartments 6 formed therein with the lower ends of said compartments opening outwardly through the bottom portion of the body and the upper ends thereof communicating with a chamber 7 formed at the center of the upper portion of the body.

The central portion of the body is formed with a hub 8 from which partitions 9 extend radially therefrom for connection with the outer wall of the body 5 and serves to form partitions between the longitudinally extending compartment 6.

The upper portion of the hub 8 terminates inwardly of the upper edge of the outer wall of the body 5 as clearly illustrated in Figures 1 and 3 of the drawings. A central bore extends through the hub 8 through which is inserted a metallic pin 10 having its opposite ends protruding outwardly from the opposite end of the hub.

To the under side of the body 5 is fitted a cap 11, likewise constructed of insulation material and also formed with a central opening through which the lower end of the pin 10 extends. A sleeve 12 is fitted about the pin 10 constructed of conductor material and provided with a flange 13 at its upper end and seated upon the upper edge of the hub 8 and with its lower end formed with a relatively slight flange 14 adapted to seat within a channeled groove formed in the flanged head 15 at the lower end of the pin 10.

A positive connection is thus provided for the pin and the sleeve at the lower end thereof. The flanged end 15 of the pin 10 extends outwardly beyond the cap 11 and constitutes one of the contact members for the plug when the same is inserted in an electric socket.

The other contact for the plug is provided by the usual metallic threaded sleeve 16 fitted about the lower portion of the body 5 and by means of which the plug is threadedly fitted in the electric socket.

5 The lower end of the sleeve 16 is turned inwardly as indicated at 17 between the cap 11 and the lower edge of the body as clearly illustrated in Figure 1 of the drawings. A 10 fusible link 18 is arranged within each of the compartments 6 and disposed vertically with their lower ends bent angularly between the inturned lower ends 17 of the threaded sleeve 16, said inturned end 17 being provided with openings through which the lower ends of the links may be inserted.

15 Pivot pins 19 extend radially of the hub 8 of the body across each of the compartments 6 and through the upper portion of the links 20 within said compartment. The links are thus normally retained in fixed position within their respective compartments.

20 A switch arm 20 is rotatably mounted on the upper portion of the pin 10 and is seated upon the upper flange 13 of the sleeve 12. The outer end of the switch 20 protrudes transversely of the upper portion of each of the compartments 6 and is adapted upon the rotation of the switch to engage the upper end of the fusible link 18.

25 It will thus be apparent that the switch 20 and links 18 serve to complete the circuit through the plug by reason of their engagement with the respective contacts formed by the pin 10 and sleeve 16. An 30 insulated pin 21 extends vertically through the switch 20 with its upper end extending above the switch and to which is attached one end of a coiled spring 22 having its opposite end attached to the upper end of the pin 10.

35 The pin 10 is stationary within the hub of the lug and accordingly the tension of the spring is utilized to rotate the switch 20 about said pin. By insulating one end of the spring from the switch the current passing through the plug will not affect the spring so as to impair the resiliency of the same.

40 A mica cover plate 26 is placed upon the upper edges of the body 5 and secured in position by a cap 23 within which is arranged a series of openings 24 registering with the compartment 6 of the body so that 45 the condition of the links 18 may be inspected.

45 It will be readily apparent from the foregoing description that should the link 18 with which the switch arm 20 is in contact, 50 become fused, the broken upper end of the link will then be permitted to swing about the horizontal pin 19 and permit the switch arm 20 to be moved into contacting position with the adjacent fusible link 18.

55 The outer ends of the pivot pin 19 are re-

cessed in the walls of the body 5 and the recess is then filled with a plastic insulation composition indicated at 25 to prevent contact between the sleeve 16 and the end of the pin 19. The action of the plug for 70 maintaining one of the unbroken links in the circuit is thus automatic.

It is obvious that my invention is susceptible to various changes and modifications in construction without departing 75 from the spirit of the invention or the scope of the appended claims, and I accordingly claim all such forms of the device to which I am entitled.

Having thus described my invention, 80 what I claim as new is:

1. A fuse plug comprising a body having a plurality of concentrically arranged compartments formed therein, a fusible link disposed within each of said compartments, 85 a pivot pin extending through the upper portion of each of said links, contact members for the plug, one of said contact members being arranged in contacting relation with one end of each of said links, the opposite end of said links being arranged for pivotal movement about its associated pivot pin upon the fusing of the link and a switch arm connected with the other of said contacts and movable in a path for successive 90 engagement with the pivoted end of said links.

2. A fuse plug comprising a body having a plurality of concentrically arranged compartments formed therein, a fusible link disposed longitudinally in each of said compartments, a pair of contact members for the plug, one of said members being disposed about the outer walls of the plug with one end extended inwardly and connected with one end of each of said links, 100 said other contact member being centrally disposed within the plug, a switch arm rotatably mounted at one end of said last named contact member and adapted for movement in a path for successive engagement with the other end of said links, 105 spring means normally urging the switch arm in one direction and a pivot pin for each of said links and extending through the end thereof adjacent said switch arm and adapted for pivotal movement upon the fusing of the link whereby to release the switch arm and permit the movement thereof for engagement with an adjacent 110 link.

3. A fuse plug comprising a body having a plurality of concentrically arranged compartments, a fusible link pivotally disposed in each compartment for movement about a 115 horizontal axis, a contact member having engagement with each of the said fusible links, a metallic pin extending centrally of the said body, a sleeve on said pin provided with a flange at its upper end, said 120

sleeve and pin constituting a contact for the said body, a switch arm rotatably mounted on the upper portion of the pin and seated upon the said upper flange of the sleeve, said switch arm having its outer end extending over each of the said compartments and adapted upon the rotation of the switch to successively engage the fusible links, and a coil spring encircling the upper end of the said pin and attached thereto with its free end connected with the switch arm for rotating the same about said pin.

In testimony whereof I affix my signature.

HRAND M. MUNCHERIAN.
